United States Patent

Des. 236,917
Patented Sept. 23, 1975

236,917

COMBINED WRITING INSTRUMENT AND CAP THEREFOR

Norman Melnick, Highland Park, N.J., assignor to Magic Marker Corporation, Cherry Hill, N.J.

Filed Apr. 2, 1973, Ser. No. 347,212

Term of patent 14 years

Int. Cl. D19—06

U.S. Cl. D19—45

FIG. 1 is an exploded perspective view of a combined writing instrument and cap therefor showing my new design;

FIG. 2 is a rear elevational view thereof;

FIG. 3 is an enlarged scale left end elevational view of the writing portion;

FIG. 4 is a right end elevational view thereof;

FIG. 5 is an enlarged scale left end elevational view of the cap portion; and

FIG. 6 is a right end elevational view thereof.

I claim:

The ornamental design of a combined writing instrument and cap therefor, as shown and described.
